TUBE BENDING DEVICE

Godfrey Park Goode, Covington, Ky., assignor to
The Lackner Company, Inc., Cincinnati, Ohio,
a corporation of Ohio

Application September 15, 1938, Serial No. 230,080

4 Claims. (Cl. 49-7)

This invention relates to devices for bending tubes and more particularly to the bending of glass tubes such as are used, for example, in connection with neon signs. It is well known that tubes going to make up neon signs must be bent at various angles and it is desirable to have a device whereby this bending can be accomplished speedily and accurately as regards the degree of bend and without collapsing the tube at the point of bend.

The objects of my invention, therefore, include the provision of a device for bending glass tubes and the like by means of which such tubes may quickly be bent and whereby the angle of bend may be accurately established and whereby the danger of collapsing of the tube at the bend is eliminated. Further objects of my invention include provision of a device as outlined above which will be simple and inexpensive to manufacture and which will not require skilled labor to operate.

These and other objects of my invention which will be pointed out hereinafter or which will be apparent to one skilled in the art upon reading these specifications, I accomplish by that certain construction and arrangement of parts of which I shall now describe an exemplary embodiment.

Reference is made to the drawing forming a part hereof and in which:

Figure 1 is a front elevation of a device according to my invention.

Fig. 2 is a horizontal cross sectional view taken on the line 2-2 of Fig. 1.

Fig. 3 is a partial side elevation thereof as seen from the right of Fig. 1.

Fig. 4 is a detailed rear elevation showing the dial.

Fig. 5 is a detailed perspective view of one of the tube clamps.

Fig. 6 is a detailed perspective view of the burner arrangement.

Figs. 7 and 8 are elevational views of pieces of tubing showing the necessary location of the point of bend for different degrees of bending.

Briefly, in the practice of my invention, I provide a framework comprising leg members 10 which may, if desired, be braced as indicated at 11, and which carry at the top a plate 12. Extending below the plate 12 and preferably integral therewith are the bending brackets 13 in which is journaled a shaft 14. This shaft, as best seen in Fig. 3, carries at its rear end a disc 15 which may, if desired, be mounted by means of a set screw passing through its hub as generally indicated at 16. The purpose of this disc will be described in more detail hereinafter. At the front there is mounted upon the shaft 14 a disc 17. This disc may, if desired, be mounted in the same manner as the disc 15. Screwed to the disc 17 is a downwardly depending strap of L-shape

18, to which is screwed another L-shaped member indicated generally at 19. The fastening means are, of course, located at the points indicated at 20. The member 19 is slotted throughout its length to accept a square headed bolt or the like, for purposes which will later be described. It should be understood that a single member could be substituted for the members 18 and 19, if desired.

10 Bolted to the plate 12 as indicated at 21, is a bracket 22 which carries the slotted extension 23. It should be understood that the members 22 and 23 could be made integral or form a single piece if desired.

15 The assembly indicated at 22 and 23 comprises the fixed limb, while the assembly indicated at 18 and 19 comprises the movable limb and clamps are provided on the respective limbs to engage a tube which is to be bent. These clamps are indicated in Figs. 1 and 3 generally at 24 and are shown in detail in Fig. 5. As will be seen from Fig. 5, these clamps include a base 26 upon which are mounted two generally L-shaped members 27 which are vertically interspaced. An opposing clamping bar 28 is pivoted on the rod 29 which extends between the member 27, and the member 28 is urged into clamping position by means of the torsion spring indicated at 30. A rod 31 may, if desired, be provided as a handle for the clamping bar 28. It should be noted that the base member 26 is provided with an elongated slot 32 for attachment of the clamp 24 into the member 23 or 19 as the case may be. By virtue of the horizontally disposed slot 32 it is possible to adjust the lateral position of the clamp for a purpose which will be described hereinafter.

20 The lower limb 19 carries an L-shaped extension 33 which is fastened by means of the nut and bolt indicated at 34. This member serves as an end gauge so that if a number of tubes are to be bent at a certain distance from their ends, the device may be set up and for successive bending operations it is only necessary to see that the tube abuts against the horizontal portion 33a of the member 33.

25 From the foregoing it will be clear that a tube to be bent is inserted into the device with its lower end abutting the portion 33a and clamped in the two clamps 24. After the area of the bend has been adequately heated it is only necessary to swing the lower limb of the device as indicated by the arrow A in Fig. 1. Referring again to the disc 15 which is shown in more detail in Fig. 4, it will be noted that this disc is provided with a notch 15a and a series of graduations 15b. Mounted on a bracket 10a is a spring member 10b having a projection 10c. It will be clear that as the lower limb is rocked in the direction indicated by the arrow A in Fig. 1 (clockwise), the disc 15 as viewed in Fig. 4 will turn in a counterclock-

wise direction until the portion 18c enters the notch 15a. Thus a tube may be bent through any desired angle without fail by simply setting the disc 15 to an appropriate graduation, it being understood, of course, that the graduations read in a counterclockwise direction from the notch 15a.

In order to soften the glass prior to bending, I provide a burner arrangement which will now be described by reference to Figs. 1 and 6. I prefer to use as a fuel a mixture of air and gas, and I therefore provide air and gas lines as indicated in Fig. 1 and provide them with appropriate valves 35 and 36. A T fitting at 37 serves to bring the gas and air lines together and the mixture passes through a flexible conduit 38 and additional piping generally indicated at 39 to the burners. The burners themselves have been deleted from Figs. 1 and 2 in the interest of clarity and the burner arrangement is shown in detail in Fig. 6. It will there be seen that the burner arrangement consists of three burner nozzles 40 arranged to surround the tube to be bent. The tube itself is indicated at 41. A simple construction may be made using simple pipe fittings and elbows by means of which the three burners may be caused to operate in a single plane. As shown in Fig. 6, in sequence, the first burner is connected by means of a T fitting 40a and the second burner by means of an elbow 40b, and a T fitting 40c. The combination of three elbows indicated respectively at 40d, 40e and 40f serves to bring the third burner 40 back to the same plane as the other two. A swivel fitting of any conventional type is provided at 42 so that the entire burner unit may be swung aside while tubing is being inserted or removed from the bending device.

Care must be taken in the bending of glass tubing that the tubing be not collapsed particularly in applications connected with neon signs. In order to avoid any such difficulty I provide two expedients. The one involves the lateral displaceability of the clamping members 24 by means of the horizontal slot construction 32. I have found that the center of the bend should be located on a line bisecting the angle of the bend and half-way between the inner and outer radius of the bend. This fact is illustrated in Figs. 7 and 8 where it will be seen that for a 90 degree bend the center of bend will be displaced from the axis of the tube by the distance x and in the case of 135 degree bend by the distance y . The distances x and y and the like can readily be determined graphically and the clamps 24 can be appropriately adjusted.

A further expedient involves the maintaining of pressure within the tube during the bending process. For this purpose I provide a T in the air line as indicated at 43, to which is connected an air line 44. The air line terminates in another T fitting 45, the end of which is left open. A pipe 46 branching from the T is connected through a flexible hose 47 to the upper end of the tube to be bent, as indicated at 48. A cork shown at 49 in Fig. 3 is inserted into the bottom of the tube. From this description it will be seen that air is constantly flowing through the pipe 44 and out through the open end of the T 45. When the tube is ready for bending the operator may place his finger over the open end of the tube 45 whereby the air pressure will be transmitted through the tubing 46 and 47 to the tube 41 which is being bent. As soon as the bending op-

eration is completed the cork 49 may be removed so that air will flow through the bent tube to cool the same. When the tube has been adequately cooled, the operator may remove his finger from the T 45, and disconnect and unclamp the tube.

It will be understood that various modifications may be made in my invention without departing from the spirit thereof, and that I do not intend to limit myself otherwise than as pointed out in the claims which follow.

Having now fully described my invention, what I claim as new and desire to secure by Letters Patent is:

15. 1. In a device for bending tubes, a fixed arm and a pivoted arm normally disposed in alignment, and tube clamps mounted respectively on said arms, said clamps being adjustable laterally in relation to said arms, whereby the position in 20 which a tube is clamped with respect to the pivot point of said pivoted arm may be varied.

2. In a device for bending tubes, a frame, a shaft rotatably mounted in said frame, an arm fixedly mounted on said frame and an arm fixedly mounted perpendicular to said shaft on one end thereof, said arms being normally in alignment, tube clamping means on said arms substantially at the adjacent ends thereof, a disc having a notch, settable fixed on said shaft, and a member mounted on said frame resiliently engaging said disc and having a portion adapted to enter said notch, whereby to limit the rotation of said shaft upon engagement thereof with said notch.

35. 3. In a device for bending tubes, a frame, a shaft rotatably mounted in said frame, an arm fixedly mounted on said frame and an arm fixedly mounted perpendicular to said shaft on one end thereof, said arms being normally in alignment, tube clamping means on said arms substantially at the adjacent ends thereof, a disc having a notch, settable fixed on said shaft, and a member mounted on said frame resiliently engaging said disc and having a portion adapted to enter said notch, whereby to limit the rotation of said shaft upon engagement thereof with said notch, said disc carrying indicia to indicate the degree of bend whereby upon setting of said disc to a desired angle a tube to be bent will be bent to said angle.

4. A device for bending tubes comprising a frame, a shaft rotatably mounted in said frame, an arm fixedly mounted on said frame and an arm fixedly mounted perpendicular to said shaft on one end thereof, said arms being normally in alignment, tube clamping means on said arms substantially at the adjacent ends thereof, means for gauging and limiting the rotation of said shaft, a burner assembly comprising a plurality of nozzles arranged to be disposed substantially radially to a tube to be bent, said burner assembly being pivotally mounted whereby it may be swung bodily aside during insertion or removal of a tube, a fuel line feeding said burner assembly, an air line and a gas line connected to said fuel line, and a branch line from said air line terminating in a flexible tube, said branch line having a by-pass opening, said flexible tubing being attachable to a tube to be bent, and means for stopping the free end of the tube to be bent, whereby upon stopping the by-pass opening pressure may be applied to the tube to be bent.
